UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

TRIMMING DEVICE FOR SEWING MACHINES.

Application filed July 29, 1919. Serial No. 314,087.

To all whom it may concern:

Be it known that I, ALBERT H. DE VOE, a citizen of the United States, residing at Westfield, in the county of Union and State 5 of New Jersey, have invented certain new and useful Improvements in Trimming Devices for Sewing Machines, of which the following is a specification, reference being had therein to the accompanying drawings.

10 This invention relates to trimming mechanism for sewing machines and it has for its object the improvement of the trimming mechanism of that type disclosed in my Patent No. 1,289,125 of December 31, 1918, 15 whereby the trimmer blade may be thrown into or out of operation.

In the preferred form of the improvement the vertically disposed reciprocatory trimmer-blade carrier is mounted adjacent the 20 needle-bar upon a pair of vertically swinging arms and receives operative movements from a suitable connection with the needle operating lever. Mounted upon the trimmer-blade carrier is a latch for establishing 25 and interrupting operative connection between the carrier and the needle-lever whereby the carrier, with its trimmer blade, may be arrested and shifted into retracted position clear of the work-support.

30 The improvement is illustrated in the accompanying drawings in which Fig. 1 is a side elevation of the machine, partly in section, showing the movable trimmer-blade in operative position; Fig. 2 is a front elevation of the machine and Fig. 3 is a sectional elevation through the line $\alpha - \alpha$ in Fig. 1, both Figures 2 and 3 showing the movable trimmer-blade in retracted position; Fig. 4 is a similar sectional elevation with the trimmer-blade in its lowest position; Fig. 5 is a sectional elevation similar to Fig. 3 showing the trimmer-blade carrier unlatched from its actuating arm and with the blade in extreme retracted position clear of the work-support, and Fig. 6 is a detail showing a portion of the actuating arm and its eccentric stud-connection with the crank-arm.

50 The improvement is embodied in a machine preferably of the chain-stitch type. It comprises the base 1, from which rises the standard 2 provided with the overhanging arm 3 terminating in the head 4 in

which are mounted for reciprocatory movement the usual needle- and presser-bars. 55 Journaled in the lower portion of the standard, lengthwise of the machine, is the main-shaft 5 having fixed upon its rear end the balance wheel 6 with the belt-groove 7. Secured to the main-shaft 5, within the base of 60 the standard 2, is the ball-eccentric 8 which is embraced by the lower end of a pitman 9 whose upper end has a ball-and-socket connection 10 with a needle-lever 11 fulcrumed upon the stud 12 rigidly secured to the overhanging arm 3. The forward end of the needle-lever has a link-connection 13 with a collar 14 clamped upon the needle-bar 15 provided with the usual needle. The collar 14 is formed with an upstanding lug 16 70 tapped to receive a pivot-screw 17 passing through a suitable aperture in the lower end of the combined link- and take-up member 18 provided with the usual thread-eye for controlling the needle-thread in the well-known manner. The upper end of the take-up member is apertured to receive a pivot-screw 19 tapped into the end of the rocker-arm 20 rigidly secured upon the rocking pin 21. The pin 21 is journaled in a suitable bearing-bracket 22 sustained by the overhanging arm 3, a collar 23, fastened upon the pin 21 by the screw 24 restraining the pin from longitudinal movement in its bearing-bracket. The construction so far described is substantially the same as that disclosed in my prior patent previously referred to.

Secured to the rocker-arm 20 by the screw 25, and disposed eccentrically with respect to the pin 21, is the roller-stud 26 upon which is fulcrumed one end 27 of an actuating arm 28 which is apertured intermediate its ends to receive a pivot screw 29 tapped into the upper end of the trimmer-blade carrier 30. The arm 28 and carrier 30 constitute an articulated endwise movable trimmer-arm and the pivot screw 29 constitutes a pivotal supporting connection between the trimmer-blade carrier 30 and its actuating arm 28, operative movements being imparted to the arm 28 by means of the needle-lever 11 through links 13 and 18, rocker-arm 20 and stud 26.

105 The lower end of the carrier 30 is split and recessed to receive a trimmer-blade 31

which is clamped therein by the screw 31'. The upper trimmer-blade 31 cooperates in the wellknown manner with a lower or stationary blade 32 removably secured in the 5 throat-plate 33.

Intermediate its ends the carrier 30 is provided with a laterally extending screw-pin 34 slidingly embraced by a boss formed upon one end of the arm 35 whose other end 10 is rigidly secured upon the rod 36 slidably mounted in bearing bosses 37 and 38 formed, respectively, upon the head 4 and standard 2. A collar 39 is adjustably secured upon the rod 36 between which and the bearing boss 38 is interposed a coiled spring 40. The arm 35 directs the endwise movements of the trimmer blade carrier and, under the action of the spring 40, maintains the upper trimmer-blade 31, when in operative position, 15 yieldingly in cooperative relation with the lower or stationary trimmer-member 32. The blade carrier 30 is provided near its lower end with a lateral arm 41 which contacts with the depending guide-member 42 secured to the bracket-arm 3 by the screws 43, thereby preventing lateral displacement of the blade-carrier under the action of the spring when in retracted position.

To permit the movable trimmer-blade 31 20 to be uncoupled from the actuating arm 28 and shifted into retracted position clear of the work-support, the carrier 30 is provided with a latch 44. The latch is pivotally supported upon the shoulder screw 45, tapped into carrier 30 and its upper end 46 is notched to form a hook adapted to engage the end of the actuating arm 28. The latch is pressed toward the actuating arm 28 by the spring 47 having one end rigidly secured 25 in a suitable aperture in the latch and its free end in sliding contact with the screw-stud 48 tapped into the carrier 30.

The latch 44 constitutes connecting means 30 between the carrier 30 and actuating arm 28 for rigidly associating these parts together and for permitting relative movement between them to allow the trimmer-blade to be thrown into or out of operation.

The latch 44 is provided with a lateral 35 stud 49 which projects through a clearance aperture 50 in the carrier 30 and which is adapted to engage an inverted detaining hook 51 formed in the end of a plate 52 secured to the head 4 by the fastening screws 53. The detaining hook 51 retains the movable blade-carrier 30 in retracted position when shifted clear of the work-support. The latch 44 is provided at its lower end 40 with a laterally extending finger-piece 54 for convenience in manipulation.

It will be observed that the actuating arm 28 and the laterally spring-pressed arm 35 constitute a pair of vertically swinging arms for pivotally supporting the trimmer-blade 45 carrier 30, one of the pivotal supporting

points 34 being intermediate the ends of the carrier which receives operative movements through one of said arms, when the latch 44 couples the carrier 30 with the actuating arm. It will also be observed that the 70 latch 44 serves as a disconnectible connection between the carrier and its actuating arm for rendering the latter ineffective.

During the operation of the machine, when the movable trimmer-blade 31 is in 75 lower or operative position, the carrier 30 receives its reciprocatory movements from the actuating arm 28 by which it is pivotally supported upon the floating fulcrum screw 29 and operatively connected by the spring- 80 pressed latch 44, as clearly shown in Figs. 2, 3 and 4.

When it is desired to throw out the movable trimmer-blade, the operator grasps the finger-piece 54 of the latch 44 and moves it 85 inwardly and upwardly, thereby uncoupling the latch from the actuating arm 28 and at the same time shifting the movable blade carrier 30 into retracted position where it is retained by engagement of the stud 49 with 90 the detaining hook 51, as represented in Fig. 5. In this position of the parts the actuating arm 28 rocks idly past the upper hooked end 46 of the latch 44 without affecting the pivotal connection 29 between the 95 actuating arm and the carrier 30.

Having thus set forth the nature of the invention, what I claim herein is:—

1. In a trimming mechanism for sewing machines, in combination, a trimmer-blade, 100 a carrier therefor, a pair of movable arms directly connected with and affording supporting means for said carrier, means for imparting operative movements to one of said supporting arms, and means including a latch for establishing and interrupting 105 operative relation between one of said supporting arms and said carrier.

2. In a trimming mechanism for sewing machines, in combination, a rocker-arm, a trimmer actuating arm operatively connected with said rocker-arm, a trimmer-blade, a carrier therefor pivotally connected with and supported by said actuating arm, and means for establishing and interrupting 110 operative connection between said carrier and said actuating arm without affecting their connection.

3. In a trimming mechanism for sewing machines, in combination, a trimmer-blade, 120 an actuating arm, a carrier for said trimmer-blade pivotally connected with and supported upon said actuating arm, and means for interrupting operative connection between the carrier and its actuating arm and retaining the carrier in retracted position 125 without affecting the pivotal connection between the trimmer carrier and its supporting arm.

4. In a trimming mechanism for sewing 130

- machines, in combination, a rocker-arm, a trimmer actuating arm operatively connected with said rocker-arm, a trimmer-blade, a carrier therefor pivotally connected with and supported by said actuating arm, and a latch sustained by said carrier for establishing and interrupting operative connection between said carrier and said actuating arm without affecting their connection.
- 5 5. In a trimming mechanism for sewing machines, in combination, a trimmer-blade, an actuating arm, a carrier for said trimmer-blade pivotally supported upon said actuating arm, a latch pivotally supported upon said carrier for establishing and interrupting the operative connection between the carrier and its actuating arm without affecting their pivotal connection, and means carried by said latch and engaging a stationary part of the machine for retaining said carrier in retracted position.
- 10 6. In a trimming mechanism for sewing machines, in combination, a rocker-arm, a trimmer actuating arm operatively connected with said rocker-arm, a trimmer-blade, a carrier therefor pivotally connected with and supported by said actuating arm, and means mounted upon said carrier for interrupting operative connection between
- 15 20 25 30 said carrier and said actuating arm without

affecting their connection to permit the manual retraction of the trimmer-blade.

7. In a trimming mechanism for sewing machines, in combination, a trimmer-blade, a carrier for said trimmer-blade, a pair of vertically swinging arms having direct pivotal connection with and adapted to support said carrier, actuating means for imparting operative movements to the trimmer-blade carrier through one of said arms, and means interposed between the last-named arm and said carrier for rendering said actuating means ineffective.

8. In a trimming mechanism for sewing machines, in combination, an eccentric actuating member, an articulated, endwise-movable trimmer-arm embracing said actuating member, a trimmer-blade carried by said trimmer-arm, means in engagement with said arm for directing the endwise movements of the latter, and connecting means carried by said arm for rigidly associating the parts thereof or for permitting relative movement between such parts to throw the trimmer-blade into or out of operation.

In testimony whereof, I have signed my name to this specification.

ALBERT H. DE VOE.
